UNITED STATES PATENT OFFICE

1,971,513

ELECTRIC OZONE GENERATOR

Edward C. Stoddard, Racine, Wis.

Application February 18, 1932, Serial No. 593,774

3 Claims. (Cl. 204—32)

The present invention relates to electric ozone generators, and is particularly concerned with ozone generating devices which are automatic in their operation so that they may be installed for domestic or business use where the ozone generator must run without much attention or care.

The ozone generators of the prior art have not been capable of being used in this manner for the reason that it was necessary to turn the generator on and off whenever the user felt that it was desirable to generate more ozone. Furthermore, the devices of the prior art have not been constructed in the form of units which can be conveniently installed in various different places where they might be used, and one of the objects of the invention is the provision of an improved ozone generator unit which may be utilized in a separate casing or which may be installed as a unit in a recess in any room.

Another object of the invention is the provision of an improved ozone generator installation which is adapted to maintain the air of a room in a proper condition, without any attention or care on the part of the user.

Another object of the invention is the provision of an improved wall installation which is completely concealed and out of the way, but which is adapted to be used in the rooms of public buildings for providing the air with a fresh supply of ozone to dissipate smoke, kill germs, and revitalize the air of the room.

Another object of the invention is the provision of an improved ozone generator having an automatic timing mechanism whereby the generator is turned on at periodic intervals and operated for a predetermined period of time so that one standard device may be adjusted by means of the timing mechanism to take care of a room of any size or an assembly of people of any particular number.

Another object of the invention is the provision of an improved ozone generator structure which is capable of economical manufacture, sturdy, efficient and capable of operation for a long period of time without need of attention or repair.

Other objects and advantages of the invention will be apparent from the following description and from the accompanying drawings, in which similar characters of reference indicate similar parts throughout the several views.

Referring to the drawings, of which there are three sheets,

Fig. 1 is a view in perspective of one of the

ozone generator units installed in an ornamental casing;

Fig. 2 is an elevational view of the mechanism in the casing, looking from the front, with the casing in section along a vertical plane parallel to the front; 60

Fig. 3 is a side elevational view of the ozone generator mechanism with the casing in section, taken on the plane of the line 3—3 of Fig. 2; 65

Fig. 4 is a similar side elevational view in partial section, showing a wall installation;

Fig. 5 is a fragmentary plan view of one of the dielectric plates and electrodes with the supporting column or standard in section;

Fig. 6 is a similar view taken from the bottom of the same dielectric plate, showing the other electrode; 70

Fig. 7 is a fragmentary sectional view taken on the plane of the line 7—7 of Fig. 5, showing the structure of the supporting standards; 75

Fig. 8 is a fragmentary plan view of one end of one electrode, showing the mode of securing a connection between the electrode and supporting standard;

Fig. 9 is a wiring diagram of the ozone generator; 80

Fig. 10 is a front elevational view of the dial and associated mechanism for the timing device;

Fig. 11 is an elevational view of the electric switch of the timing device with other parts of the timing device in section, taken on the plane of the line 11—11 of Fig. 12, looking in the direction of the arrows; 85

Fig. 12 is a side elevational view of the timing mechanism; 90

Fig. 13 is an enlarged sectional view of the shaft and dial of the timing device, showing the mode of support of the dial and its pointer on the shaft, the section being taken on a vertical axis 95 through the shaft; and

Fig. 14 is a fragmentary view of a part of a modified unit having a different type of electrode.

Referring to Figs. 1 to 3, 10 indicates in its entirety the ozone generator unit which is preferably enclosed in a casing 11 and provided with a timing mechanism 12. The casing 11 may be made of various materials, but is preferably constructed of electrical insulating material such as wood or a molded phenolic condensation compound, and provided with front and rear ventilation openings 13, 14, preferably covered with a screen or grating 15, 16.

In the type of unit having a separate casing, I prefer to locate the timing mechanism in the 110

back of the casing, as shown in Fig. 3, but where the casing 11 is installed in a wall I prefer to locate the timing mechanism 12 in the front so that it is readily accessible. The casing of the 5 wall installation is preferably provided with a cover plate 17 consisting of a grating which may be formed of metal and covered with porcelain, and the grating is provided with a plurality of apertures 18 through which the ozone is delivered. That portion of the grating not in line with the fan 19 is utilized for permitting the inflow of air into the casing 11 so that air flows in at the bottom of the casing and is driven out of the central portion of the grating 17, carrying with 10 it the newly generated ozone.

The present unit is so small and its depth from front to back such that it can be conveniently installed in any ordinary wall, as shown in Fig. 4.

20 The ozone generator is preferably energized from the ordinary source of lighting current which is used for lighting, and for this purpose the portable unit shown in Fig. 1 may be provided with a connection cord 20, having the usual plug 21 for engagement with the wall socket.

25 In Fig. 4 the connections from the lighting circuit are made by conductors carried by conduit 22 to the switch box 23, and thence to the ozone generator through the leads 20. The device is thus provided with a main control switch 30 24 for shutting off the ozone generator during such time when it is not desired to use the generator at all, and the same result may be accomplished by pulling out the plug 21 in Fig. 1.

35 Referring to Figs. 2, 3 and 9, the ozone generator preferably comprises a step-up transformer 25 which may be enclosed in a molded insulating casing 26 of phenolic condensation compound, usually called bakelite. The casing 26 is provided with a plurality of feet 27, having holes for the reception of screw bolts or screws 28 for securing the unit in place in the casing 11. The transformer casing 26 also provides a support for a motor 29 for driving a fan 30, and the 40 motor may be secured to the transformer casing by any convenient fastening device, such as, for example, the supporting base 31, which is secured to the transformer casing by screw bolts 32 threaded into the transformer casing.

50 The transformer casing is preferably provided with brackets or integral attaching supporting flanges 33, each having an aperture 34 for receiving the column or standard 35 which supports the ozone generator electrodes or plates. 55 The standards 35 may consist of elongated rods, each provided with a head 36 and a threaded portion 37, and the standard may be secured to the transformer casing by means of the nuts 38 which also serve to clamp the end of conductor 39 to the rod 35. When nut 38 is driven home 60 the end of conductor 39 is clamped between the nut and a washer 40, and the rod is secured to the transformer.

It should also be understood that transformers 65 having a metal casing may be utilized, in which case appropriate metal brackets would be formed upon the outside of the transformer casing for supporting the motor and the rods 35. The rods 35 would be insulated from the metal brackets 70 by appropriate porcelain insulators or tubes, since the rods 35 are intended to provide both a connection and a support for the electrodes of the ozone generator. In a similar manner, the conductor 41 is connected to the supporting rod 42 at the other side of the transformer, the con-

ductors 39 and 41 comprising leads from the secondary or high voltage side of the transformer 25.

Above the transformer the rods 35, 42 support a plurality of electrodes 43, 44, arranged in groups, and one electrode of each group is arranged on 80 each side of each dielectric plate 45. The dielectric plates 45 are preferably formed of glass, but various other forms of dielectric may also be used. Each glass plate 45 has a pair of apertures 46, one for each rod 35, 42. The electrodes of the ozone generator are preferably connected together in the manner shown in Fig. 9, all of the electrodes on one side of the glass plate 45 being connected to one side of the transformer secondary and the electrodes on the other side of the glass plates 45 being connected to the other lead from the transformer secondary. This may be accomplished by making the electrodes shorter than the glass plates so that the electrodes 44 do not extend over far enough to strike the rod 42, while the electrodes 43 do not extend far enough to the left to engage the rod 35.

90 The electrodes preferably consist of metal plates, the plates being channeled in section and provided with a flat body 47 having transversely 95 extending retaining flanges 48, 49 along each edge.

95 The flanges 48, 49 are spaced sufficiently from each other to engage on the opposite sides of the insulating strip 49'. The flat body 47 of each 100 electrode plate is placed adjacent the glass plate 45, and the electrode is retained in such position by the insulating strip 49', which is also provided with an aperture 50 for receiving the rod 35 or 42.

105 In order to space the plates from each other, the rods are also provided with spacers 51 which may consist of a piece of insulating tubing surrounding the rod and engaging adjacent insulating strips 49 at each end of the tube. When all 110 of the glass plates, metal electrodes, insulating strips and spacers have been assembled on the rods, they are secured in place by nuts 52.

115 In order to assure a connection between the metal electrodes 43, 44 and the rods 35, 42, the electrode plates are preferably provided with a 120 slit 53 and the aperture 54 in each electrode plate is slightly smaller than the rod 35 so that when the electrode plates are assembled on the rods 125 the metal plates are sprung apart at the slit 53 and the legs 54, 55 at the ends of each plate 130 resiliently grip the rods to assure a good connection. The electrodes are thus clamped between the glass plates and insulating strips at the rods 35, 42, but the metal electrodes and glass plates may become separated slightly at points in between the supporting rods so as to permit the air to pass between the glass plates and the metal electrodes.

135 The motor and fan 29, 30 may consist of any convenient type of fan adapted to drive the air past the electrodes to continuously remove the ozone generated from the vicinity of the electrodes.

140 The ozone generator is preferably provided with a timing device 12 adapted to be adjusted to operate the generator for a predetermined period of time and to shut the generator off for a predetermined period of time. The standard unit already described is capable of producing enough ozone for a small room when operated 145 for a few minutes each hour, and the unit should not be operated after the room has been provided with a sufficient amount of ozone. Furthermore, the amount of ozone required in the room will vary with the number of people assembled there, 150

and no single unit can be depended upon to supply a sufficient amount of ozone unless it is made large enough to take care of the maximum requirements which may be expected and also 5 adapted to be adjusted to take care of any ordinary requirements without further attention.

By means of the timing arrangement 12, the present ozone generator can be adjusted for small rooms or large rooms, and the supply of 10 ozone can be increased when a large assembly is to be present in the room.

In order to accomplish this result, the generator is preferably provided with a timing device 12 which may consist of a spring wound clock, 15 but preferably consists of an electric clock adapted to be energized from the same source of current. The electric clock consists of a synchronous electric motor 56 which may be any of the standard clocks on the market or a specially constructed clock. The electric motor 56, through 20 a system of gearing, drives a shaft 57, which is provided with a dial 58 and a pointer 59. The dial and pointer 58, 59 may be carried by a hub 60. The hub 60 is provided with a collar 61 engaging 25 the back side of the dial 58 and a riveted or spun shoulder 62 on the other side of the dial 58 for securing the dial 58 in place.

The pointer 59 is frictionally mounted on the hub 60 in such manner that it may be rotated to 30 any desired position with respect to the dial 58. The dial 58 is provided with a plurality of scale divisions 63 and indicia 64 corresponding to the number of minutes in an hour.

In some embodiments of the invention the cycle 35 of the ozone generator may be carried on over a different period of time, such as a half hour or a quarter hour, but the hourly cycle is preferred for the reason that modern clock mechanisms are provided with shafts rotating at this speed.

40 The dial 58 is provided with a cam 65 located on its periphery and provided with a sloping surface 66. The cam surface 66 is adapted to engage a pin 67 which is carried by the switch lever 68 to move the switch lever 68 backward in Fig. 11.

45 The complete timing mechanism may be mounted upon a panel 69 by means of a plurality of screw bolts 70. The panel is provided with apertures 71 for passing the pin 67, 72 and for passing the pin 73. A latch 74 is fixedly mounted on a 50 shaft 75, which is rotatably mounted in an aperture in the panel 69. A coil spring 76 has one end secured to the shaft 75 to actuate the cam 74 in a clockwise direction in Fig. 10, and the other end of the spring is secured to the panel 69 by a screw bolt 78. Latch 74 comprises a sheet metal member formed with a hook or retaining surface 79 and formed with a transversely extending end 80. The end 80 extends into the path of movement of the end of the pointer 59. The dial 58 and hub 60 may be rotated freely on the reduced end 81 of the shaft 57, but may be secured in place by 60 the nut 82. The pointer 59 is secured in place relative to dial 58 by the frictional engagement of the end of the pointer with the hub 60, the 65 pointer being split at the point 83.

Referring to Fig. 11, the rear side of the panel 69 preferably carries a pair of pivotally mounted switch levers 68, 84. The switch levers may consist of strips of insulating material pivotally 70 mounted by means of pins 85 on the supporting block 86. Each switch lever 68, 84 carries a contact spring 87, 88, the exact position of which may be adjusted by means of a screw bolt 89 threaded through the insulating strip 68 or 84. 75 A spring 90 has one end hooked about a screw

bolt 91 carried by lever 68 and the other end hooked about a screw bolt 92 carried by switch lever 84. The spring 90 tends to urge the switch levers 68, 84 together. Another spring 93 has one end secured to panel 69 by means of a pin 94, 80 and the other end secured to a pin 95 carried by the end of switch lever 68. A stop member 96 prevents counterclockwise rotation of switch lever 68 when the parts are in the position of Fig. 11. 85

The operation of the timing mechanism is as follows: When the shaft 57 is rotated in a counterclockwise direction, as in Fig. 10, by the clock motor, the dial 58 and pointer 59 rotate with the shaft. The cam 65 is adapted to cam pin 67 downward, carrying with it the lever 68. Lever 68 is then moved in a clockwise direction, in Fig. 11, against the tension of spring 93 until contact 87 is brought in engagement with contact 88. Contact 88 is then also rotated counterclockwise to the position of Fig. 11, in which the pin 73 is moved down until it is engaged by the hook 79. The latch 74 tends to rotate clockwise in Fig. 10 into position to engage and latch the pin 73. The cam 66 thus latches the switch lever 84 in the position of Figs. 10 and 11 and after the cam 100 passes the switch lever 68 moves back again to the position of Fig. 11, but switch lever 84 is retained in the position of Fig. 11. 95

It will be evident that cam 65 moves the switch members to open position, where they are latched. 105 As the rotation of the dial 58 progresses with the pointer 59, the pointer 59 comes into engagement with the transverse end 80 of the pawl 74 and unlatches the pawl 74 against the tension of spring 76. This permits switch lever 84 to move 110 counterclockwise in Fig. 11 under the influence of spring 90 to close the circuit. The pointer 59 is thus adapted to unlatch the switch and close the circuit.

The angularity between the cam 65 and the 115 pointer 59 determines the length of time during which the circuit will be closed.

In the embodiment illustrated, the circuit is opened at the point 0 and closed at the point 15, fifteen minutes later, but the time during which 120 the switch is closed may be adjusted to any value within the limits of an hour by adjusting the position of the pointer 59.

Referring to Fig. 9, this is a wiring diagram of the complete circuit. The leads 97, 98 may be 125 connected directly to the terminals of the clock motor of the timing device 12. The clock motor is adapted to operate at all times, while the fan motor is periodically turned on or off. The primary of the transformer may have one end connected by a conductor 99 to the conductor 100 and the other end connected by a conductor 101 to contact 88. The other contact 87 may be connected by conductor 102 to conductor 97. The conductor 100 leads from conductor 98 to the fan 130 motor 29, and conductor 103 leads from the other terminal of the fan motor 29 to the conductor 101. By tracing the circuits, it will be observed that both the transformer primary and the fan motor are controlled by the contacts 87, 88. 140

Referring to Fig. 14, this is a modification in which the electrodes are shaped to permit the passage of air. The electrodes 104, 105 may be provided with transverse corrugations extending in the direction of the air flow and with transversely turned ends 107 adapted to engage in the slots 106 in the insulating strips 99. In some embodiments of the invention the electrodes may also be made of screen to permit the access of air to the point of generation of the ozone. 145

The operation of the complete installation is as follows:

The device may be energized through an appropriate source of lighting current, and when 5 the timer has moved to a predetermined position the pointer 59 will trip the latch 74 and close the circuit. The transformer 25 will then generate a sufficiently high voltage to energize the 10 electrodes 43, 44 with a high potential, and the electrical discharge between the electrodes causes the generation of ozone. The oxygen in the air surrounding the electrodes is changed into ozone and the ozone generated is immediately driven out of the casing and from the vicinity of the 15 electrodes by the current of air from the fan 30. This action continues for the predetermined period of time, which is determined by the angularity between the cam and pointer, and which may be adjusted as desired. The length of the 20 period through which the generator should run will be determined by the size of the room, the conditions in the room, and the purposes for which the ozone generator is used. The ozone generated has strong oxidizing properties and 25 may be used for bleaching, oxidizing, sterilization of the air or drinking water, and for reconditioning the air in homes, offices, factories, and the like. It may also be used in laundries for giving 30 the freshly laundered goods a fresh odor and sterilizing the goods.

It will thus be observed that I have invented an improved ozone generator which is adapted to be manufactured in one standard unit to take care of a multiplicity of different conditions. The 35 ozone generator need only be operated for a predetermined part of each time period, and the time period may be made as short as desired.

The present ozonizer is sturdy, efficient, capable of economical manufacture and sale, and it may 40 be installed in public buildings for continuous operation under automatic control so that no attention is required for a long period of time.

While I have illustrated a preferred embodiment of my invention, many modifications may

be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States is:

1. In an electric ozone generator, the combination of a pair of electrically conducting standards with a dielectric plate carried by said standards, an electrode carried by one side of said plate engaging one standard and a second electrode engaging the other standard and located on the other side of said plate, said electrodes each having a split end in resilient engagement with its standard.
2. In an electric ozone generator, the combination of a pair of electrically conducting standards with a dielectric plate carried by said standards, an electrode carried by one side of said plate engaging one standard, a second electrode engaging the other standard and located on the other side of said plate, said electrodes each having a split end in resilient engagement with its standard, and an insulating member outside each electrode for holding said electrodes on said plate.
3. In an ozonizer, the combination of a transformer having an enclosing casing with laterally projecting lugs carried by said transformer, a pair of frame members carried by said transformer and extending through said lugs, a plurality of glass plates carried by said frame members, insulating spacers between said glass plates on said frame members, and metallic electrodes on opposite sides of each glass plate, said electrodes having perforated split ends engaging said frame members, and said frame members being constructed of electrically conductive material and said electrodes having guide flanges on both sides engaging the sides of an aligning strip of insulating material located on opposite sides of each glass plate.
